(57) **CLAIM**

The ornamental design for a hearing aid and charger set as shown and described.

DESCRIPTION

FIG. 1 is a front, right and top perspective view of a left ear of a hearing aid and charger set shown separately to show aspects of the design that are not visible when combined, showing my new design;

FIG. 2 is a rear, left and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, right and top perspective view of a right ear of the hearing aid and charger set shown separately to show aspects of the design that are not visible when combined;

FIG. 10 is a rear, left and bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a front, right and top perspective view of a charger of the hearing aid and charger set shown separately to show aspects of the design that are not visible when combined;

FIG. 18 is rear, left and bottom perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof;

FIG. 24 is a bottom plan view thereof;

FIG. 25 is a front perspective view of the hearing aid and charger set shown in an open state; and,

(Continued)

FIG. 26 is a rear, left and bottom perspective view thereof. The broken lines depict portions of the hearing aid and charger set that form no part of the claimed design.
